UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, ENGLAND.

LOADING APPARATUS OF HEAVY GUNS.

1,094,128.

Specification of Letters Patent. Patented Apr. 21, 1914.

Application filed September 30, 1911. Serial No. 652,191.

To all whom it may concern:

Be it known that we, ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to the Loading Apparatus of Heavy Guns, of which the following is a specification.

This invention relates to the loading apparatus of heavy guns, and has particular reference to gun loading cages of the kind in which means are provided for permitting the powder charges to descend into the ramming position after the projectile has been rammed into the gun and the rammer withdrawn. For this purpose the cage is usually furnished with doors which normally retain the powder charges in their position above the projectile in the cage, the said doors being under the control of a manually operated lever carried by the said cage.

According to our invention we provide means under the control of the rammer whereby the powder charges will on the return movement of the rammer after the projectile has been rammed automatically assume their ramming position so that the liability of mistake on the part of the operator in releasing the powder charges by hand as heretofore is eliminated. The said means may comprise a hydraulic or other actuating device so constructed and arranged that when the cage assumes its fully raised position suitable mechanism on the cage for operating the doors will be capable of becoming temporarily engaged with the actuating device after the projectile has been rammed and of becoming disengaged from the actuating device when the cage descends after the loading operation has been effected.

In order that the said invention may be clearly understood and readily carried into effect, we will describe the same more fully with reference to the accompanying drawings in which:

Figures 1 and 1^a represent a diagrammatic side elevation, and Fig. 2 is a rear ele-

vation showing one form of our invention employed in conjunction with a rammer of the flexible chain type.

55

A is the gun, B the slide frame, B' the loading arm, B² the rammer and C the gun loading cage. The powder doors of the loading cage C are in the example shown under the direct control of a cam C' which is connected by means of a longitudinally displaceable rod c' with the arm c² of a spring controlled bell crank lever C² the spindle c^{2x} of which is pivotally mounted on the gun loading cage. In order to enable 60 the bell crank lever to become engaged with the actuating device when the cage reaches its fully raised position and after the projectile has been rammed, the other arm c³ of the said bell crank lever is provided with 65 a roller C³ or the like the axis of which is capable of inward and outward movement relatively to the pivot of the bell crank lever C². This roller is under the control of a spring c⁴ that tends to keep it in its inward 70 position. Attached to the ram D' of the hydraulic cylinder D² carried by the loading arm is a member D formed with a slot d. As the cage assumes its fully raised position 75 the roller C³ by coming against the underside of the member D is moved outward against the resistance of the spring c⁴ and assumes the position shown in the drawings. The hydraulic cylinder D² communicates by 80 the pipe b' with a valve B^x carried by the slide frame B and is supplied with constant pressure fluid by the pipe d^x. The said valve B^x is so arranged in relation to the rammer B² that when the latter reaches its 85 fully withdrawn position it co-operates with the stem of the valve B^x to displace it and put the cylinder D² to exhaust through the pipes b', b², the constant pressure fluid from the pipe d^x then moving the ram D' toward 90 the right and retaining it in this position as 95 shown in the drawings.

The valve B^x is in the form of a differential ram and is under the control of constant pressure fluid supplied by the pipe b so that when the rammer B² leaves its fully 100 withdrawn position to ram the projectile and moves away from the stem of the valve B^x the latter is displaced toward the left by the pressure fluid acting thereon and thereby

admits pressure fluid from the pipe b through the pipe b' to the hydraulic cylinder D^2 and moves the member D outward into such a position that the slot d therein comes above the roller C^3 which then under the action of its spring c^4 engages in the said slot whereby a temporary engagement is effected between the door actuating mechanism and the aforesaid hydraulic device.

- 10 After the projectile has been rammed and when the rammer has returned to the fully withdrawn position, it coöperates with the stem of the valve B^x , thereby moving the latter toward the right into a position to 70
 15 place the hydraulic press D^2 to exhaust, through the pipes b' , b^2 as aforesaid. Constant pressure fluid supplied by the pipe d^x then acts on the opposite side of the ram D' and moves the latter to its normal position, carrying with it the roller C^3 engaging 75
 20 in the slot d in the member D connected to the said ram. As this roller is carried by the arm c^3 of the bell crank lever C^2 , the latter moves against the resistance of a 80
 25 spring C^0 and displaces the cam C' to operate the powder doors thereby allowing the lower powder charges to descend into the space previously occupied by the projectile. 85
 30 On the rammer leaving its withdrawn position to ram the said charges, the valve B^x is displaced as aforesaid to admit pressure fluid to the press D^2 through the pipe b' thereby moving the ram D' to the left and by means of the roller C^3 on the arm c^3 of 90
 35 the bell crank lever, causing the latter to resume its normal position and again close the doors of the loading cage. When the rammer, after ramming the first two charges, returns to its fully withdrawn position, the aforesaid sequence of operations 95
 40 is repeated and the remaining charges are permitted to assume the loading position and then rammed. When the loading cage C descends, the roller C^3 (carried by the 100
 45 bell crank lever C^2 on the cage) moves out of engagement with the slot d in the member D and the bell crank lever C^2 is then operated by its spring C^0 to close the powder doors. 105
 50 We wish it to be understood that we do not desire to limit our invention to loading apparatus in which the gun can be loaded at any angle of elevation nor to apparatus in which a flexible rammer is employed. 110
 55

What we claim and desire to secure by Letters Patent of the United States is:—

1. In gun loading apparatus, the combination with the rammer and the loading cage, of means under the control of the rammer for enabling the powder charges in the cage to automatically assume their ramming position on the return movement of the rammer after performing a ramming 115
 60 operation. 120
 65

2. In gun loading apparatus, the combination with the rammer, the loading cage and the members for retaining the powder charges in position in said cage, of means for automatically opening said members on the return movement of the rammer. 125
 70

3. In gun loading apparatus, the combination with the rammer, the loading cage and the members for retaining the powder charges in position in said cage, of an hydraulic device under the control of the rammer for automatically opening said members on the return movement of the rammer. 130
 75

4. In gun loading apparatus, the combination with the rammer, the loading cage and the members for retaining the powder charges in position in said cage, of operating mechanism for aforesaid members carried by the cage, an hydraulic device under the control of the rammer, means for temporarily engaging said device with the said mechanism when the cage is in the loading position, and means for automatically operating said hydraulic device on the return movement of the rammer. 80
 85

5. In gun loading apparatus, the combination with the rammer, the loading cage and the members for retaining the powder charges in position in said cage, of operating mechanism for aforesaid members carried by the cage, an hydraulic device under the control of the rammer, means for temporarily engaging said device with the said mechanism when the cage is in the loading 90
 95 position and a valve under the control of the rammer for automatically operating the said device on the return movement of the rammer. 100
 105

6. In gun loading apparatus, the combination with the rammer, the loading cage and the members for retaining the powder charges in position in said cage, of operating mechanism for aforesaid members carried by the cage, an hydraulic device under the control of the rammer, means for temporarily engaging said device with the said mechanism when the cage is in the loading position, a valve controlling the movements of the said device and means for displacing said valve on the return movement of the rammer. 110
 115

7. In gun loading apparatus, the combination with the rammer, the loading cage and the members for retaining the powder charges in position in said cage, of operating mechanism for aforesaid members carried by said cage, an hydraulic ram, an extension of said ram, means for temporarily connecting said extension to a member of said mechanism when the cage is in the loading position and a valve under the control of the rammer for causing the ram to open the said members on the return movement of the rammer. 120
 125
 130

8. In gun loading apparatus, the combination with the rammer, the loading cage and the members for retaining the powder charges in position in said cage, of operating mechanism for aforesaid members carried by said cage, an hydraulic ram, an extension of said ram formed with a slot, a roller on a member of said mechanism adapted to engage in said slot, and a valve under the control of the rammer for causing the ram to open the said members on the return movement of the rammer.

In testimony whereof we affix our signatures in presence of two witnesses.
